UNITED STATES PATENT OFFICE.

WILLIAM H. PRINZ, OF OAK PARK, ILLINOIS, ASSIGNOR OF ONE-THIRD TO CHARLES A. PLAMONDON AND ONE-THIRD TO GEORGE PLAMONDON, OF CHICAGO, ILLINOIS.

MALT-KILN.

No. 897,781.

Specification of Letters Patent.

Patented Sept. 1, 1908.

Application filed March 25, 1907. Serial No. 364,485.

To all whom it may concern:

Be it known that I, WILLIAM H. PRINZ, a citizen of the United States, residing at Oak Park, in the county of Cook and State of Illinois, have invented certain new and useful Improvements in Malt-Kilns, of which the following is a specification, reference being had to the accompanying drawings.

My invention relates to malt-kilns of the general type illustrated and described in my patents, No. 515,840, dated March 6, 1894, and No. 605,012, dated May 31, 1898, in which the malt is placed in compartments on the upper floors of the building and is supplied with hot air from a furnace located on the ground floor.

My present invention has particularly to do with malt-kilns in which malt compartments are provided on two or more floors, provision being made for dumping the floor or floors to deposit the malt in the compartments of the lower floor,—the upper floor being used for withering the malt and the lower floor or floors for finishing it. In the accompanying drawings I have illustrated only two floors, but it will be understood that more than two may be employed if desired.

In a malt-kiln it is very important in drying the malt to expel the moisture of the wet malt on the upper or withering floor quickly, the rapidity of the drying depending to a certain extent upon the character of the malt wanted, and this must be done by supplying to it a large amount of cool air; while in the case of the malt on the finishing floor a less amount of air at a higher temperature is used.

My present invention has for its object to provide a new and improved construction of kiln by which the air supplied to the different floors may be accurately controlled, both as to quantity and temperature; also to provide improved means for properly mixing the air and for regulating the amount of vacuum maintained in any of the drying chambers; also to provide a construction by which the kiln may be operated more economically as regards fuel consumption, at the same time producing malt of superior quality by reason of the fact that the air supplied may be more accurately controlled,

as above stated. I accomplish these objects as illustrated in the drawings and as hereinafter described.

55

That which I believe to be new is set forth in the claims.

In the accompanying drawings,—Figure 1 is a cross-sectional view of my improved kiln; and Fig. 2 is a longitudinal section thereof.

Referring to the drawings,—3—4 indicate the side walls of the building, 5 being an intermediate partition which forms one of the side walls of the kiln proper.

65

6—7 indicate the end walls of the building.

8 indicates the kiln furnaces, which, as shown in the drawings, are on the ground floor. 9 indicates the furnace room, which is also on the ground floor and communicates 70 with the external atmosphere by an opening 10 having a door 11 which may be of any suitable construction. By opening the door external air may be admitted directly to the furnace-room.

75

12 indicates heating coils, which extend across the furnace-room 9 a short distance from the opening 10, forming a fresh-air chamber 13, as shown in Fig. 2.

14 indicates a valve arranged at the upper 80 portion of the chamber 13, which when in a horizontal position closes said chamber at the top, thereby compelling air admitted through the opening 10 to pass through the coils 12, which are heated, preferably by exhaust 85 steam. The valve 14 may be turned to an upright position, thereby permitting the air in the chamber 13 to pass directly upward therefrom into a flue 15 arranged adjacent to the wall 6, as shown in Fig. 2. A similar flue 90 16 is provided at the opposite end of the kiln, which communicates at its lower end with the chamber 9.

17 indicates a finishing floor provided with one or more compartments 18 adapted to 95 contain malt. Said compartments are provided with perforated dumping floors 19 of any suitable type, on which the malt is placed while being finished. By dumping said floors the finished malt may be dumped into 100 hoppers 20 placed below the finishing floor, as shown in Fig. 1, and delivered therefrom in any suitable way, as by screw-conveyors 21, shown also in Fig. 1.

22 indicates a hood or hoods which deflect the malt into the hoppers 20 in the usual way.

It will be understood that the space between the furnaces 8 and the finishing floor 17 forms a hot-air chamber 26, as it receives the hot air from the furnaces.

23 indicates a series of levers by which the various sections of the dumping floor 19 may be tilted to dump the finished malt, and 24 indicates the usual helical agitators for turning the malt in the finishing compartments. Said turners are rotated by the usual rope drive mechanism, as illustrated.

15 25 indicates an opening affording communication between the flue 15 and the hot-air chamber 26, above referred to. Said opening or passage is controlled by a valve 27, as shown in the drawings,—28 being a lever by which said valve is rocked to control the operative area of the opening 25. 29 indicates a similar opening between the flue 15 and the finishing chamber 17, which opening is also controlled by a valve 30.

25 33 indicates an imperforate dumping floor, which lies above the finishing chamber on a level slightly below the upper ends of the flues 15—16, as shown in Figs. 1 and 2. Said dumping floor is dumped by a lever 34.

30 35 indicates a valve in the upper end of the flue 15 for controlling the operative area thereof.

35 36 indicates a withering chamber, which lies above the dumping floor 33 and is provided with one or more withering compartments 37 having perforated dumping floors 38 similar to the dumping floor 19 and controlled by levers 39, shown in Fig. 1. The withering compartments are provided with 40 helical turners 40 similar to the turners 24.

41 indicates a fan at the top of the building, which communicates with the upper portion of the withering chamber, so that it draws air from said chamber and discharges it at 45 the top of the building.

42 indicates a number of distributing conveyers for delivering malt to the withering compartments. Said conveyers, however, have nothing whatever to do with my present 50 invention, and further description thereof is deemed unnecessary.

The flue 16 is equipped with valves and valve passages in the same manner as the flue 15,—the parts being correspondingly 55 numbered, and a heating coil 12 and valve 14 are also provided for controlling the admission of air at the opposite end of the building.

If desired, by closing the valves 11 external 60 air may be shut off, all the air admitted to the upper floor being supplied from the kiln furnaces 8, and such air may be permitted to pass up through the malt in the finishing compartments, or a greater or less part of it 65 may be conducted around the finishing

chamber by opening the valves 27 and 35 so as to permit the air to rise through the flues 15—16 without passing through the perforated floor 19. By this arrangement hot air directly from the furnaces may be admitted to the withering floor. Furthermore, air may be admitted to the finishing floor above the malt from the flues 15—16 by opening the valves 30 and closing the valves 35. Again, fresh air may be admitted directly to the flues 15—16, or it may be admitted to said flues after passing through the heaters 12, and may be distributed to the several chambers by properly adjusting the several valves. The space above the dumping floor 80 33 constitutes a chamber in which air from the air shafts or flues 15—16 may be thoroughly mixed before being admitted to the malt on the withering floor, thus making it possible to very accurately control the quantity and temperature of the air supplied to the malt.

That which I claim as my invention and desire to secure by Letters Patent, is,—

1. A malt-kiln, comprising a furnace, a plurality of perforated floors above said furnace, means for conducting heated air from said furnace through the malt on said floors means for conducting external air through the malt on said floors, and auxiliary means 95 for heating the external air.

2. A malt-kiln, comprising a furnace, a finishing floor, a withering floor above said finishing floor, means for conducting heated air from the furnace through the malt on said 100 finishing floor, means for conducting heated air from the furnace through the malt on the withering floor without its passing through the malt on the finishing floor, and means for supplying external air to the malt on the 105 finishing floor.

3. A malt-kiln, comprising a furnace, a finishing floor, a withering floor above said finishing floor, means for conducting heated air from the furnace through the malt on 110 said finishing floor, means for conducting heated air from the furnace through the malt on the withering floor without its passing through the malt on the finishing floor, and means for conducting external air to the 115 malt on the withering floor.

4. A malt-kiln, comprising a furnace, a finishing floor, a withering floor above said finishing floor, means for conducting air from the furnace to said floors means for conducting external air through the malt on the finishing floor, and auxiliary means for heating the external air.

5. A malt-kiln, comprising a furnace, a finishing floor, a withering floor above said finishing floor, means for conducting air from the furnace to said floors means for conducting external air through the malt on the withering floor, and auxiliary means for heating the external air.

6. A malt-kiln, comprising a furnace, a finishing floor, a withering floor above said finishing floor, an imperforate floor between said finishing and withering floors, and means 5 for conducting heated air from said furnace to the withering floor and to the finishing floor.
7. A malt-kiln, comprising a furnace, a finishing floor, a withering floor above said 10 finishing floor, an imperforate floor between said finishing and withering floors, means for conducting heated air from said furnace to the withering floor and to the finishing floor, and means for controlling the distribution 15 of air to said floors.
8. A malt-kiln, comprising a furnace, a finishing floor, a withering floor above said finishing floor, an imperforate floor between said finishing and withering floors, means for 20 conducting heated air from said furnace to the withering floor and to the finishing floor, and means for supplying external air to said withering and finishing floors.
9. A malt-kiln, comprising a furnace, a 25 finishing floor, a withering floor above said finishing floor, an imperforate floor between said finishing and withering floors, means for conducting heated air from said furnace to the withering floor and to the finishing floor, 30 means for controlling the distribution of air to said floors, and means for supplying external air to said withering and finishing floors.
10. A malt-kiln, comprising a furnace, a finishing floor, a withering floor above said 35 finishing floor, an imperforate floor between said finishing and withering floors, means for conducting heated air from said furnace to the withering floor and to the finishing floor, means for supplying external air to said 40 withering and finishing floors, and auxiliary means for heating the external air.
11. A malt-kiln, comprising a furnace, a finishing floor, a withering floor above said 45 finishing floor, an imperforate floor between said finishing and withering floors, means for conducting heated air from said furnace to the withering floor and to the finishing floor, means for controlling the distribution of air to said floors, means for supplying external 50 air to said withering and finishing floors, and auxiliary means for heating the external air.
12. A malt-kiln, having a furnace, a finishing floor, a withering floor above the finishing floor, a flue for conducting air to the malt 55 on said withering and finishing floors, a passage admitting external air to said flue, an auxiliary heating device, and a valve for admitting external air directly to said flue or for causing it to pass through said auxiliary 60 heating device before being admitted to said flue.
